SPRING BIASED SAFETY CATCH FOR
SEPARABLE FASTENERSFelix Holzknecht, Vancouver, British Columbia,
Canada

Application August 22, 1947, Serial No. 770,099

2 Claims. (Cl. 24—222)

1

This invention relates to separable fasteners for garters or other articles.

An object of the invention is the provision of a separable fastener in which one of the elements of the fastener is in the form of a headed shank adapted to be received by a bayonet slot in the other element with means for preventing the headed shank from becoming disengaged from the slot.

Another object of the invention is the provision of a separable fastener in which one element of the fastener is in the form of a button having a shank adapted to be received by a bayonet slot of the other element of the fastener with a pivoted catch engaging the shank below the button for preventing disengagement of the button from the bayonet slot.

A further object of the invention is the provision of a separable fastener in which one element of the fastener is in the form of a shank having the free end provided with a button adapted to be received by a keyhole slot in the second element of the fastener, the button being prevented from disengagement from the slot by a spring-pressed catch normally disposed beneath the button for retaining the shank in the narrow portion of the slot, said catch being moved manually away from the button to permit release of the same, the shank being secured to one portion of the garment, while the other element is attached to another portion of said garment.

The invention consists in the novel construction, arrangement and combinations of parts hereinafter more particularly described and claimed.

In the drawings:

Figure 1 is a view in perspective of a garter showing a separable fastener applied thereto.

Figure 2 is an enlarged fragmentary view in perspective of the garter showing a catch released to permit disengagement of the elements of the separable fastener.

Figure 3 is an enlarged plan view of one element of the separable fastener.

Figure 4 is a view in elevation of the element of the fastener illustrated in Figure 3 showing the inside of said element.

Figure 5 is an enlarged plan view of a plate forming one of the members of the element shown in Figures 3 and 4, and

Figure 6 is an enlarged plan view of a second plate forming another member of the element of the fastener illustrated in Figures 3 and 4.

Referring more particularly to the drawing A represents one element of a separable fastener

2

secured to one portion 10 of an article of wearing apparel, which is illustrated as a garter. The second element of the fastener generally designated by the letter B is attached to a second portion of the article which in this instance is shown as a loop 11 at one end of an elastic band 12. The other end of the band is attached at 13 to the portion or tab 10. A second separable fastener 14 is employed for attachment to the upper end of a sock.

The element A of the fastener is of a well known type in which a shank 15 rises from a base 16 having a loop 17 attached by threads to the portion 10 of the garter. A button or enlarged head 18 is formed at the free end of said shank.

The element B of said fastener consists principally of two plates 20 and 21. The plate 20 has an elongated narrow slot 22 adapted to receive the loop 11 of the elastic band 12. A bayonet or key-hole slot 23 has its wider portion 24 opening into the slot 22 while the narrow portion 25 of the slot 23 opens into the wider portion 24. The plate, so far described, is standard construction and the head of the element A is inserted through the wider portion 24 of the slot 23 so that the shank 15 may be moved within the narrow portion 25 of the slot 23 for connecting together the elements of the separable fastener and the two portions 10 and 11 of the garter. The plate 20 is provided with two perforations 26 for a purpose which will be presently described.

The plate 21 has an elongated slot 30 adapted to align with the slot 22 of the plate 20 for the reception of the loop 11. This plate is further provided with two perforations 31 adapted to align with the perforations 26 in the plate 20. A lip or catch 32 projects from the plate 21 outwardly from the slot 30 and substantially covers the wider portion 24 of the key-hole slot when the plates 20 and 21 are aligned as shown in Figure 3.

A U-shaped wire 33 has its legs 34 received by the aligned perforations in the plates 20 and 21. The free ends 35 of the legs are bent at an angle and lie in flat contact with the outside face of the plate 21. The wire 33 together with the legs 34 form a hinge for the plates 21 and 20 so that the free ends of the plates may be swung outwardly from each other or towards each other.

A U-shaped spring wire 40 (Figures 3 and 4) has its legs 41 bent around the legs 34 of the U-shaped hinging member 33 as shown at 42. One leg 41 of the spring wire presses against the inner face of the plate 20 while the other leg

presses against the inner face of the plate 21 for retaining the free ends of the plates outwardly of each other and the catch 32 covering the wide portion 24 of the key-hole or bayonet slot 23 to prevent the head 18 and the shank 15 from becoming disengaged from said slot by retaining the shank in the narrow portion 25 of the slot 23 which is formed in a narrow projection 43 on the plate 20.

Before attempting to connect the members A and B of the separable fastener, it will be necessary to press the free ends of the plates 20 and 21 together. This action will cause the lip or catch 32 to be elevated above the wider portion 24 of the slot 23 so that the head or button 18 may be inserted through the portion 24 of the bayonet slot 23 and the shank 15 is then moved into the narrow portion 25 of the slot.

The free ends of the plates 20 and 21 are released and the spring legs 41 of the member 40 will force the free ends of said plates apart causing the lip 32 to rest over the portion 24 of the slot 23 thereby preventing movement of the shank to the wide portion of the slot. In these positions of the parts, it will be impossible to dislodge the member A from the member B of the separable fastener.

While I have shown and described a preferred construction of the fastener, this is by way of illustration only, and I consider as my own all such modifications in construction as fairly fall within the scope of the appended claims.

What I claim:

1. A safety catch for a fastener including a headed shank, a plate having a bayonet slot at one end to receive the shank, means preventing disengagement of the shank from the bayonet slot comprising a second plate having one end covering the wider portion of the slot, said plates having aligned spaced perforations, a U-shaped member having legs thereof inserted through the perforations, the free ends of the legs bent back

against one of the plates and a U-shaped spring member between the plates having the legs thereof bent around the adjacently disposed legs of the first U-shaped member, the free end of one leg of the spring member pressing against the inner face of one plate, the free end of the other leg pressing against the inner face of the other plate for retaining the outer ends of the plates outwardly of each other and the first mentioned end of the second plate over the wider portion of the slot.

2. A safety catch for a fastener having a headed shank, a plate having a bayonet slot at one end to receive the headed shank, means preventing disengagement of the headed shank from the slot comprising a second plate, said plates having aligned perforations inwardly from one end, said end of the second plate covering the wider portion of the slot, a U-shaped member having the legs thereof received by the perforations for hingedly connecting the plates together, the free ends of the legs being bent over the back of one of the plates, and a spring member connected to the U-shaped member forcing the other ends of the plates outwardly from each other for normally retaining the first mentioned end of the second plate over the wider portion of the slot, the second mentioned ends of the plates being manually movable towards each other for raising the first mentioned end of the second plate from the slot to release the shank.

FELIX HOLZKNECHT.
